MOLD FOR MAKING HOLLOW CONCRETE CASTS

Fred E. Kruckenberg, Fort Wayne, Ind.

Application September 14, 1938, Serial No. 229,949

7 Claims. (Cl. 25—130).

This invention relates to molds for making hollow concrete casts such as burial vaults.

An object of the invention is to provide a mold with a base, outer end and side walls detachably connected together, and an expandible core provided with mechanism whereby to selectively expand or contract the walls of the core.

Another object of the invention is to construct the core of flexible metallic sheets provided on their inner faces with reenforce members so arranged as to permit the top wall and those portions of the side walls adjacent thereto to be flexed upon expansion or contraction of the core structure.

15 And a further object of the invention is to provide a mold having an expandible core provided with mechanism for expanding and contracting same, which mechanism includes operating members that are manipulated from the exterior of the mold.

Other objects and advantages of the invention appear in the following description.

An illustrative embodiment of the invention is shown in the accompanying drawings, in which:

25 Fig. 1 is a side elevation of a mold in which the invention is incorporated, portions thereof being cut away;

30 Fig. 2 is an end view of the mold, the outer side walls and a concrete cast formed in the mold being in section;

Fig. 3 is a section of Fig. 1 on the line 3—3 thereof, the outer walls being omitted and the core shown in expanded position;

Fig. 4 is a fragmentary section of Fig. 1 on the 35 line 4—4 thereof;

Fig. 5 is a fragmentary section of Fig. 1 on the line 5—5 thereof;

Fig. 6 is a detail horizontal section showing the manner of connecting the side and end plates of 40 the core with the bus bars;

Fig. 7 is a vertical transverse section of the core and base, the section being on the line 3—3 of Fig. 1, and the core being in contracted position; and

Fig. 8 is a fragmentary plan view of the mold, 45 the outer end and side walls being in section on the line 8—8 of Fig. 1.

The illustrative embodiment of the invention is constituted of a base, an exterior mold form, an expandible core and actuating mechanism associated with various parts of the core provided with means for operating the mechanism.

The base

There is provided a horizontal rectangular 55 base-frame 1, preferably formed of side and end

beams 2 and 3 made of angle-iron shapes, and a series of guide-rods 4, spaced apart, are mounted transversely in the base-frame with their opposite ends secured in the vertical flanges of the corresponding side-beams. Also, upon the top flanges 5 of the beams, which lie in a common horizontal plane, are secured iron channels 5 arranged to form an open groove that extends continuously and entirely around the base-frame, said guide-rods and channels being for purposes hereinafter mentioned.

The mold form

The exterior of the mold is constituted of outer end and side walls 6 and 7 respectively disposed in vertical planes and arranged in rectangular formation. The end and side walls each have secured upon their outer faces horizontal angle-bars 8—9 so disposed that when said walls are arranged in operative position, the ends of the bar 9 on the side walls extend over and rest upon the corresponding projecting ends of the bars 8 on the end walls, and there are provided pins 10 that extend through the overlapping ends of said bars by which said bars are detachably secured together, thus to hold the mold walls in operative position.

When the mold walls are positioned upon the base, their lower edges extend into the groove, afforded by the iron channels 5, and bear outwardly against the outer upturned flanges 11 thereof, thereby confining the mold walls in definite operating position.

The core

A hollow shell is formed of flexible sheet metal which has an arcuate top plate 12, end plates 13—14 and side plates 15. The upper edges of the side plates are inturned and abut the corresponding outer edges of the top plate 12, the inturned portions of the side plates being preferably shaped to form rounded flexible shoulders 16. The top plate is in two parts 12'—12" that extend longitudinally with respect to the shell with their inner edges abutting each other. Said parts are connected together by transversely disposed flexible metallic straps 17 secured to the inner faces of said parts at points spaced apart from each other and which permit upward flexure of the top plate along the abutting line of its two parts. The ends of said straps extend under the inturned portions of the side plates and are secured thereto thus to hold the abutting edges of the top plate and side plates together.

The plates 13—14 that form the ends of the shell are secured respectively at their outer edges

to the corresponding ends of the side plates 15, there being a vertically disposed angle-iron 18 attached to the inner faces of the connected plates. The inner edges of the plates 13-14 abut each other when the core is adjusted into operative position, and the upper edges of said plates are shaped to conform to the arcuate top plate 12 and underlie to a partial extent the corresponding ends of said top plate. When in operative position, the end plates 13-14 extend in a common vertical plane but are sufficiently flexible to permit disalignment thereof so that upon contraction of the shell the inner edges of said end plates overlap each other, as shown in Figs. 4 and 5, thus to permit upward flexure of the top plate 12 and inward movement of the side plates 15.

Upon the inner faces of the side plates 15 are secured vertically disposed angle-bars 19 the lower ends of which extend beyond the corresponding lower edges of the side plates 15 and have secured thereto corresponding bus-bars 20 through which the guide-rods 4 in the base loosely extend and upon which said angle-bars have sliding movement axially with respect to said guide-rods. The connections between the angle-bars 19 and the bus-bars 20 preferably are made by means of bent bolts 21, and the ends of the bus-bars are secured to the angle-irons 18 that connect the corresponding ends of the side and end plates by means of brackets 22 (Fig. 6).

Upon the inner face of each plate 13-14 is secured a ledge 25, the upper flange 26 of which extends inwardly and underlies the corresponding end of the top sheet 12 and is disposed flush with the curved upper end of the plate to which it is attached. These ledges afford support for the ends of the top plate and prevent obstruction of the end plates with the top plate when the former are moved inwardly beneath the top plate.

Along the inner edge of each end plate 13, upon the inner face thereof, is secured a cleat 23, preferably formed of angle-iron, so disposed that when the end plates 13-14 are aligned, the cleat overlaps the inner edge of the end plate 14. Also, upon the inner faces of the end plates 13-14 are secured vertically disposed reenforce bars 24, spaced apart approximately midway between the outer and inner edges of said plates, that prevent flexure of said plates upon a horizontal axis. The shell thus constructed constitutes an expandible core for the mold.

The actuating mechanism

Within the core there is arranged mechanism by means of which the walls of the shell are placed in definite operative position on the base, as when the core is expanded, and also for contracting the core when required. The actuating mechanism consists of a beam 27 having connected therewith, at their inner ends, toggle arms 28 by means of bent bolts 29. The outer ends of said toggle arms are pivotally connected with the upper ends of the angle-bars 19 on the side plates 15. The beam 27 has attached thereto jack-bars 30, the lower ends of which have connection with corresponding actuating cranks 31, so that the top and side plates of the shell are moved accordingly as the cranks are turned. The shafts 32 of said cranks are provided with supports consisting of crossbeams 33 secured to the bottom of the base-frame 4, in transverse position relative thereto, and bearing straps 34 secured to said crossbeams in which said shafts are journaled.

Also, there are provided other cranks 35 the shafts 36 of which are similarly mounted in bear-

ing straps 37 on corresponding crossbeams 38 secured to the bottom of the base-frame. A lever 39 is pivotally connected at one end thereof to the bar 24 on each end plate 13 at a point thereon adjacent its upper end, the connection being made preferably by a bent bolt 40. Said lever also has connection by means of another bent bolt 41 with the corresponding bar 23 on the plate 13. The free end of each lever 39 has contact with the bar 24 on the corresponding end plate 14 when the end plates 13-14 are moved into abutting position, thus securing proper alignment thereof when the core is expanded.

Each lever 39 is pivotally connected by means of a bolt 42 with one end of a connecting bar 43 that has pivotal connection at its opposite end with the corresponding crank 35, so that upon movement of the crank 35 the end plate 13 is actuated through the medium of the lever 39 accordingly.

A second lever 44 is pivotally connected at one of its ends to the bar 24 on the corresponding end plate 13 at a point adjacent the lower end thereof by means of a bent bolt 45 and is similarly connected by a bent bolt 46 with the cleat 23 adjacent the lower end thereof. The free end of the lever 44 has contact with the bar 24 on the plate 14 when the plates 13-14 are moved into alignment, thus sustaining the end plates in proper operating position. In each end beam 3 of the base-frame there is provided a jack-screw 47 disposed to move inwardly or outwardly accordingly as turned, the inner end of which extends loosely through the corresponding lever 44 and has thereon collars 48 that bear upon opposite sides of said lever, so that when said jack-screw is turned in one direction or the other the lever 44 is actuated accordingly.

In the side beams 2 of the base-frame there are also provided jack-screws 49 that have operative relation with the corresponding bus-bars 20, which, when said screws are turned inwardly said bus-bars are flexed, causing inward movement of the side plates 15, or, when turned outwardly causes the lower extremities of the side plates 15 to bear against the inner lips 50 of the corresponding iron channels 5.

When the core structure is positioned in connection with the base, it receives support upon the guide-rods 4, and the side plates 15 are relatively movable thereon outwardly to their operative positions against the inner lips 50 of the iron channels 5, or are movable inwardly, by action of the jack-screws 49.

The heads of the bolts 47 and 49 extend outwardly from the base-frame where they are accessible for manipulation, and the shafts 32 and 36 extend outwardly through the adjacent side beam 2 and have thereon corresponding operating levers 32'-36' by which said shafts are manipulated.

Operation

In operation, the top plate 12, side plates 15, and the end plates 13-14 are moved into operative or expanded position by manipulation of the operating levers 32'-36' and the jack-screws 49 and 41. When thus positioned the lower marginal edges of the side plates 15 and end plates 13-14 bear against the upturned lip 50 of the iron channel 5. The outer end and side walls 6 and 7 are then positioned on the base-frame with their lower edges adjusted in the groove of the iron channels 5 against the outer upturned flange 11 thereof, said walls being secured together by the pins 10 that are inserted through the extremi- 75

ties of the bars 8 and 9. Concrete in a plastic state is then poured into the space between the core and the outer mold walls and spread over the top of the core to a suitable thickness. Also, in practice, a suitable reinforce wire netting (not shown) is inserted so as to become imbedded in the concrete cast 51 as in the usual practice.

After the concrete cast has set, or substantially solidified, the outer mold walls are removed, and after the cast has completely set, the core is contracted by manipulation of the jack-screws 47 and 49 and the operating levers 32 and 36', which causes inward movement of the side walls 15 and end walls 13 and flexure of the top plate 12 as well as the shoulders 16. In this manner pressure of the core plates against the cast is universally removed therefrom, thereby permitting the cast to be bodily lifted free from the mold.

Variations from the particular construction above disclosed may readily be made by exercise of engineering skill without departure from the spirit or scope of the invention, and the following claims are intended to be inclusive of such variations.

25 What I claim is:

1. A mold for making hollow concrete casts including a base, an outer wall structure carried by the base, a core mounted on the base and including side walls and a top, means connecting the top and side walls to provide for movement of the latter toward and away from each other, end walls for the core composed of sections having confronting edge portions which are movable toward and away from each other, members threaded through the base and having means for rotating same externally of the base, means to connect the threaded members to the sides, whereby to move the sides toward and away from each other, upon rotation of the members, other members threaded through the base adjacent each end of the core and having means for rotating same exteriorly of the base, and means to connect said other threaded members to one of the adjacent sections of each core end for moving one section at each end toward and away from the other upon rotation of said other threaded members.

2. A mold in accordance with claim 1, wherein there are means operable exteriorly of the mold for moving the upper portions of the sides toward and away from each other, and wherein there are other means operable exteriorly of the mold for moving the upper portion of one of the sections of the respective core end walls toward and away from the other.

3. A mold in accordance with claim 1, wherein the means for connecting said other threaded members to the sections of the core ends each includes a lever which is pivoted at one end to one of the sections and has its other end overlapping the other section, and wherein the said other threaded members are rotatably connected to the levers.

4. A mold in accordance with claim 1, wherein there are means operable exteriorly of the mold for moving the upper portion of one of the sections of the respective core end walls toward and away from the other and which includes a lever pivoted at one end to one section and having its opposite end overlapping the other section.

5. A mold in accordance with claim 1, wherein there are vertical members connected to the sides, wherein there are bus bars connected to the lower ends of the vertical members and to which the first named threaded members are connected and wherein there are means having connection with the upper portions of the vertical members for moving the upper portions of the sides toward and away from each other.

6. A mold for making hollow concrete casts including a base, an outer wall structure carried by the base, a core mounted on the base and including side walls and a top, means connecting the top and side walls to provide for movement of the latter toward and away from each other, end walls for the core composed of sections connected to the side walls having confronting edge portions which are movable toward and away from each other, means operable exteriorly of the mold and connected to the sides for moving the upper portions of the sides toward and away from each other, means operable exteriorly of the mold and connected to the sides to move the bottoms of the sides toward and away from each other, means operable exteriorly of the mold and connected to one of the sections of the respective core end walls for moving same toward and away from the other at their upper portions, and means operable exteriorly of the mold and connected to one of the sections of the core ends for moving same toward and away from the other core end section at their lower portions.

7. A mold in accordance with claim 6, wherein the top of the core is flexible whereby same is simultaneously flexed during contraction of the core so as to be moved away from the concrete cast.

FRED E. KRUCKENBERG. 55
